UNITED STATES PATENT OFFICE.

JULIUS G. STRADER, OF POWELLTON, WEST VIRGINIA, ASSIGNOR OF TWO-THIRDS TO WILLIAM N. PAGE AND DAVID T. EVANS, OF SAME PLACE.

NUT-LOCK.

SPECIFICATION forming part of Letters Patent No. 403,968, dated May 28, 1889.

Application filed February 2, 1889. Serial No. 298,476. (No model.)

To all whom it may concern:

Be it known that I, JULIUS GEORGE STRADER, a citizen of the United States, residing in Powellton, county of Fayette, and State of West Virginia, have invented certain new and useful Improvements in Nut-Locks, of which the following is a specification.

My invention relates to that class of nut-locks in which a key is made to engage with a washer or plate on the bolt, and also to engage with a polygonal nut to lock it in place.

The object of my invention is to simplify and improve the construction of such nut-locks, render them strong and durable, secure, and easily manipulated; and to this end my invention consists in providing a washer or plate on the bolt, in forming a recess in the rear face of the washer or plate, and in providing a locking-key consisting of two arms separated by an intervening space, one of said arms adapted to lie in the recess in the rear face of the plate and the other arm adapted to lie close to the face or front of the plate in engagement with the nut. The arm which lies in the recess in the rear face of the plate or washer is preferably extended beyond the outer end of the other arm, and is provided with a lug, nose, or lip, which engages with the side of the plate or washer and locks the key to the plate.

In the accompanying drawings, illustrating my invention, Figure 1 is a side elevation of a section of rail with my improvements applied. Fig. 2 is a view of the same, partly in cross-section and partly in elevation; and Fig. 3 is a perspective view of the bolt, nut, plate, and key.

I have shown my improved nut-lock applied to an ordinary track-rail, the rail A and fish-plate B being of any suitable construction; but the fish-plate is preferably provided with an inclined laterally-projecting flange, B', as indicated in the drawings. The bolt C passes through the rail and the fish-plate in the usual way, and carries a nut, D, which may be square or polygonal, but preferably hexagonal, as shown. Between the nut and the vertical face of the fish-plate B is interposed a plate or washer, E, preferably square, as shown, and made to fit neatly between the lower edge, a,

of the rail and the upper face of the extension B' of the fish-plate. The washer or plate E is provided on its rear lower side or face with a recess, e. This recess is preferably formed to extend from the extreme lower edge 55 of the plate upwardly toward the bolt, and preferably inclined from the lower edge upwardly, as indicated in Fig. 2. The key F is shown in detail in Fig. 3. It consists of two arms, f and f', separated by an intervening 60 space, f². The arms are joined at their inner ends, f³, and at their outer ends are separated. The arm f' extends a short distance beyond the arm f. The arm f is preferably formed with an inclined lower edge to correspond with 65 the inclination of the upper face of the fish-plate extension B'. The arm f' is preferably raised slightly above the lower face of the arm f, and its outer end is turned up slightly and provided with a lug, lip, or nose, f⁴. By sliding the arm f' into the recess e in the plate E the arms will straddle the plate, and when placed in proper position the lug, nose, or lip f⁴ will spring back and engage with the side of the plate E, thereby securely locking the 70 key to the plate. The lug, lip, or nose f⁴ is preferably rounded on its upper end, so as to yield readily when unusual force is applied to withdraw the key from the plate.

It will be understood that the nut is first 80 screwed home and brought to a position in which one of the sides or faces will be parallel with the extension of the fish-plate. The key is then inserted and engages with the plate E, the outer arm, f, of the key passing 85 under the nut and fitting it closely, so that the nut cannot be further moved either way until the key is withdrawn.

I claim as my invention—

1. The combination, substantially as hereinbefore set forth, of the rail, the fish-plate having a lateral extension, the bolt and nut for securing the fish-plate to the rail, the washer lying against the vertical face of the fish-plate and having a recess in its lower rear 95 face, the key having an arm adapted to fit said recess, and an outer arm arranged on the outside of the plate or washer and engaging with the nut.

2. The combination, substantially as here- 100

inbefore set forth, of the rail, the fish-plate having an inclined lateral extension, the plate or washer arranged against the vertical wall of the fish-plate and extending to its lateral extension and provided with a recess in its lower rear face, the bolt and nut for securing together the rail, the fish-plate, and the plate or washer, and the key consisting of two arms separated as described and joined at one end, one of said arms being inclined or beveled on its lower face, the other of said arms

being raised slightly above the lower face of the other arm and provided with a lug, lip, or nose on its outer side to engage with the plate or washer.

In testimony whereof I have hereunto subscribed my name.

JULIUS G. STRADER.
